UNITED STATES PATENT OFFICE

NICHOLAS M. OEHLMERG, OF CHICAGO, ILLINOIS

ORTHOPEDIC DEVICE

Application filed December 31, 1930. Serial No. 505,755.

My present invention relates to the provision of improvements in orthopedic devices, and an object of my invention is to provide a device for the correction of various inequalities and weaknesses of the human body, and particularly to provide a device which may be used for balancing the two sides of the body, namely, the right and left sides. It is well known that many children 10 are weak in some manner and strong in others, and my present invention may be used under proper instructions and care to correct such conditions. Another object of 15 the invention is to provide a simple device of the character described, in that it is easy to manufacture and easy to maintain.

A further object is the provision of a device of the character described which may be used to correct an abnormality of the legs 20 or arms, the right leg and right arm when the left side is normal, the right leg and left arm when the remaining members are normal, and various other combinations of weaknesses.

25 Other objects will appear hereinafter.

In the drawings,—

Fig. 1 is a perspective view of one form of my device;

30 Fig. 2 is a section view, taken substantially on the line 2—2 of Fig. 1;

Fig. 3 is a view partially in section and partially in elevation, the sectional portion being taken substantially on the line 3—3 of Fig. 2;

35 Fig. 4 is a detail view of the sprocket wheel, shaft and other parts, and the portions in section are shown substantially on the line 4—4 of Fig. 3;

Fig. 5 is a detail view, partly in section 40 and partly in elevation, and taken substantially on the line 5—5 of Fig. 1;

Fig. 6 is a detail view of the seat or saddle retaining and adjusting parts of my device, and the parts in section are shown substantially on the line 6—6 of Fig. 1;

45 Fig. 7 is a detail view of the connection of crank arms with the shaft of the sprocket wheel, and the parts in section show the recesses of the shaft which are adapted to receive a bolt from the crank arm in order to

hold the crank arm on the shaft in a rigid manner;

Fig. 8 is a detail view of the shaft and manner of attaching a crank arm so that the shaft and crank arm will turn as one unit; 55 and

Fig. 9 is a view partly in section and partly in elevation, taken substantially on the line 9—9 of Fig. 8.

Referring more particularly to the drawings, this form of my invention is provided with a frame or supporting member 10, seat or saddle 11, saddle post 12, crank arms 13 for use by the hands, and crank or pedal arms 14 for use by the feet. A housing 15 is provided for the covering of the sprocket wheel, chain and other portions of the present form of my device. Suitable handles 16 and suitable pedals 17 are provided for the use by the person employing the device. It can be seen that the present form of my device is provided with two saddles and may be used by two persons jointly, that is, one person employing a handle and pedal, or another combination of these. 75

In Figs. 2, 3, 4, 7, 8, and 9 the internal working parts of the device are shown clearly and the device is provided with a suitable sprocket wheel 18, shaft 19, and chain 20. Each shaft is provided with recesses 21 for the reception of bolts 22 which extend through crank arms 13 and 14 and maintain the crank arms in such a manner that they will turn with the shaft, or upon the disengagement of bolts 22 the shaft may turn independently of the crank arms. 80

As shown more clearly in Figs. 8 and 9, recesses 21 are rendered more accessible and more easily found by the provision of inclined surfaces 23 which are widened and gradually converge to the size of recesses 21; these inclined surfaces 23 are desirable for the purpose of effecting a more ready engagement of the bolts by the recesses 21. In order to facilitate the last mentioned operation, that is, in engaging the shaft by bolts 22, an indicator or washer 24 provided with a lug 25 for designating the position at which the shaft is located at any particular time, and in order to maintain this washer or indicator in the same relative position, 85

100

tion, appropriate lug portion 26 on the washer is engaged by a recessed slot 27 of shaft 19; that is, the indicator is maintained at all times in the same position on the shaft.

5 Suitable anti-friction ball races 28 may be provided for the reduction of friction in the turning of the shaft.

The crank arms are maintained on the shaft by means of bolts 29 which are provided 10 with enlarged heads which may be used for the purpose of holding the shaft in a particular location while bolts 22 are turned into recesses 21. It can be seen that there are two recesses in each shaft, and they are located 15 approximately 180 degrees from each other so that they are on opposite sides of the shafts.

For the provision of a device which may be used by different sized individuals, saddle post 12 is provided with slots 30 through 20 which bolt 31 is adapted to be inserted into the tubular top bar or frame 10; the saddle may be thus raised or lowered as desired.

Housing 15 is provided with cup-like portions 32 in which are adapted to rest bearings 25 33, and suitable supporting plates 34 are provided for sustaining the weight of the shaft for the upper crank arms, as distinguished from the pedal arms. As can be seen in Fig. 1, housing 15 is also provided with lugs or 30 ears 35 which are suitably slotted, and plates 34 are tapped to receive a bolt through ears 35 for the purpose of holding the shaft from upward movement. Plate 34, as viewed from the right of Fig. 1, is removable and may be 35 removed by disengaging bolts 36 from appropriately tapped portions of the top bar or frame 10. Housing 15 is also provided with L-shaped lugs 37 which are adapted also to hold housing 15 and parts within it from 40 vertical movement. The lower cup-like portions of housing 15 are also provided with ears or lugs 38 which are provided with appropriate slots through which are adapted to be received bolts for engagement by appropriately tapped recesses in the lower bar 45 members of frame 10.

As can be seen from the foregoing description, my device may be used for giving exercise to the arms and legs, and because of the 50 provision of oppositely positioned recesses in the shafts, the device may be adjusted to respond to what might be termed reciprocatory motion, that is, with one hand and one foot up and one hand and one foot down, or by 55 proper adjustment these movements may be changed to what may be termed unisonous movement, that is, movement by having both hands in the same vertical position and the feet likewise in the same vertical position. 60 In order to effect the last mentioned adjustment, it is necessary only to loosen bolts 22, turn crank arms 13 and pedal arms 14 into similar positions. If the particular individual is weak on the left side and normal on 65 the right side, the crank arms and pedal arms

of the right side may be disengaged by disengaging bolts 22 on the right side, and thus leaving them free. It can be seen that the left side only would then be turned with shaft 33.

70 For the correction of certain deficiencies of the body it is desirable to reverse the movements of exercises, making the movements what might be termed reciprocatory, and also to make them what might be termed unisonous, as above described. My device may be used for all these movements for shafts 19, and sprockets 18 may be turned in either direction and the reciprocatory and unisonous movement may be provided for as before 80 described.

Two individuals may use the device at the same time for the exercising of their respective right members and their left members, and thus for children an element of amusement or sport may be found in using the device.

85 While I have described and illustrated one form of construction for carrying my invention into effect, it is capable of variation and modification without departing from the spirit of the invention, and I therefore do not wish to be limited to the precise details of construction as set forth, but desire to avail myself of such variations and modifications as come within the spirit of the invention.

90 What I claim as new and desire to secure by Letters Patent is:

A device of the character described comprising a frame, a seat mounted on said frame, means on said frame for supporting a shaft, a shaft supported by said means, a sprocket wheel affixed to said shaft, two sockets in and adjacent each end of said shaft and placed diametrically opposite each other, and a pair of crank arms adapted to slide onto said shaft and be affixed thereto by a pin passing through said crank arms and into either of said oppositely placed sockets.

95 In testimony whereof I have signed my name to this specification.

100 NICHOLAS M. OEHLMERG.
